UNITED STATES PATENT OFFICE

161,675

COMBINED FOUNTAIN BRUSH AND RAZOR UNIT

Henry W. Bauder, El Paso, Tex.

Application September 2, 1949, Serial No. 4,837

Term of patent 7 years

(Cl. D22—3.1)

To all whom it may concern:

Be it known that I, Henry W. Bauder, a citizen of the United States of America, residing at El Paso, in the county of El Paso and State of Texas, have invented a new, original, and ornamental Design for Combined Fountain Brush and Razor Unit, of which the following is a specification, reference being had to the accompanying drawing, forming part thereof.

In the drawing:

Fig. 1 is a perspective, plan view of the combined fountain brush and razor unit.

Fig. 2 is an elevational view thereof.

I claim:

The ornamental design for a combined fountain brush and razor unit, as shown.

HENRY W. BAUDER.
